INTERLOCKED STRUCTURE

Hippolyte W. Romanoff, New York, N. Y.

Application February 4, 1939, Serial No. 254,641

10 Claims. (Cl. 189—34)

My invention relates to interlocked structures and has particular reference to structures formed of beams supporting flat panels.

My invention has for its object to provide an interlocked structure which can be assembled of preformed beams made of sheet steel or other suitable sheet material, the assembling being accomplished by simply interlocking the beams without any additional fastening means such as riveting, welding, etc.

Another object of my invention is to provide a structure of a type suitable for supporting flat panels in spaced relation to each other, the panels being assembled in two spaced planes if desired, so that the complete structure represents a hollow wall of great strength and rigidity. The structure is so made that the panels are locked on the beams without any additional fastening means such as screws, etc. The panels if desired, may be made of glass.

My invention is more fully described in the accompanying specification and drawing in which—

Fig. 1 is a fractional view of my structure in the process of assembling the same.

Fig. 2 is a side view of a beam used in my structure.

Fig. 3 is an end view of the beam.

Fig. 4 is a similar view of the beam with the ends bent inwardly for assembling the side panels.

Fig. 5 is a sectional view of another modification.

Fig. 6 is a perspective view of still another modification.

My interlocked structure consists of beams 1 formed of sheet steel or other suitable material such as fiber, cardboard, etc. The beams are of a U-shaped section and are provided with recesses with shoulders 2 at the junction of the two sides of the U with the bottom wall of the U, the depth of the recess corresponding to the thickness of panels 3 which may be of sheet metal, building board, glass, etc.

The edges of the beam are bent out forming flanges 4 for engaging the edges of the panels 3. The width of the beam must be at least twice the width of the flange so that the panels can be inserted in their place at the beams by squeezing together the flanged sides as shown in Fig. 4. The beams are provided with slots 5 at spaced intervals corresponding to the length of the panels, the width of the slots corresponding to the overall thickness of the beam. The slots extend half way through the depth of the beam so that the beams can be assembled together by joining the slotted portions as shown in Fig. 1. Rectan-

gular panels 3 are placed on the shoulders 2 being retained by the flanges 4. For assembling the panels the flanges are bent inwardly as shown in Fig. 4 and then spread apart by spacing wedges or bars 6 which may be made of wood as in Fig. 1 or of a suitable fire resisting material such as asbestos board, etc. The wedges can be also made of iron in the form of inverted channels or U-shaped beams 7 as shown in Fig. 4.

A modified construction is shown in Fig. 5, the beam 8 being of a simple U-shaped section without shoulders and flanges. The panels 9 are made in the form of long strips of metal (or glass or other material if desired) abutting the edges of the sides of the beam and held in place by flanges 10 of wedge members 11 made as U-shaped beams of the depth about one half the depth of the beams 8. Stiffening ribs 12 may be provided in the members 11. Ribs 13 may be provided in the walls of the beams 1 and 8, engaging corresponding notches 14 in the edges of the beams at the slot 5. The beams are thereby effectively interlocked when the wedges are placed in position, preventing the members of the structure from being separated or jarred loose.

The beams 1 may be placed endwise in pairs against each other as shown in Fig. 6, being held together by flat separators or boards 15. These boards have slots 5 opposite each other; otherwise, construction is similar to one shown in Figs. 3 or 5.

My structure can be conveniently used for building walls of houses, floors, ceilings, etc. The panels can be made of glass, transparent or translucent as desired, or of any ordinary building material, corrugated or flat sheet iron, building board, etc. Strong cellular boards can be also made by my method of paper or fiber, the strength being greatly enhanced by gluing the parts together.

I claim as my invention:

1. An interlocked structure comprising a plurality of U-shaped beams undercut at spaced intervals by slots having width of the beams, the beams being joined together at right angles to each other by interlocking the undercut portions thereby forming a plurality of rectangular cells, and means to press the sides of one beam against the abutting edges of the transverse beams.

2. An interlocked structure comprising a plurality of U-shaped beams undercut at spaced intervals by slots having width of the beams, the beams being joined together at right angles to each other by interlocking the undercut portions thereby forming a plurality of rectangular cells,

- and wedge members inserted between the outer portions of the sides of the beams for pressing the sides of the beams against the abutting edges of the transverse beams.
5. An interlocked structure comprising a plurality of U-shaped beams having sides spaced apart, the bridge portions of the beams having recesses and shoulders, the sides having outwardly extending flanges, the beams having slots 10 cut through the bridge portions at spaced intervals, the width of the slots corresponding to the overall thickness of the beams and extending about half way through the beams, and panels fitted at their edges between the shoulders of 15 the longitudinal beams and flanges of the transverse beams.
4. An interlocked structure comprising a plurality of U-shaped beams and panels, the beams having recesses and shoulders at the bridge portions 20 for the edges of the panels and having slots cut through the bridge portions at spaced intervals, the width of the slots corresponding to the overall thickness of the beams, the beams being joined together by interlocking the slotted 25 portions thereby forming a plurality of cells between the sides of the adjacent beams, the panels fitting in the cells and resting on the beam shoulders, and means to retain the panels against the shoulders.
30. 5. An interlocked structure comprising a plurality of U-shaped beams and panels, the beams having recesses and shoulders at the bridge portions for the edges of the panels and having slots cut through the bridge portions at spaced 35 intervals, the width of the slots corresponding to the overall thickness of the beams, the beams being joined together by interlocking the slotted portions thereby forming a plurality of cells between the sides of the adjacent beams, the panels fitting in the cells and resting on the beam shoulders, means to retain the panels against the shoulders, comprising flanges extending outwardly from the edges of the beams over the edges of the panels.
45. 6. An interlocked structure comprising a plurality of U-shaped beams and panels, the beams having recesses and shoulders at the bridge portions for the edges of the panels and having slots cut through the bridge portions at spaced 50 intervals, the width of the slots corresponding to the overall thickness of the beams, the beams being joined together by interlocking the slotted portions thereby forming a plurality of cells between the sides of the adjacent beams, the panels fitting in the cells and resting on the beam shoulders, means to retain the panels against the shoulders, comprising flanges extending outwardly from the edges of the beams over the edges of the panels, the flanges being relatively
- narrow, not exceeding one half of the overall thickness of the beams, so as to admit of insertion of the panels by squeezing together the sides of the beams.
7. An interlocked structure comprising a plurality of U-shaped beams and panels, the beams having recesses and shoulders at the bridge portions for the edges of the panels and having slots cut through the bridge portions at spaced intervals, the width of the slots corresponding 10 to the overall thickness of the beams, the beams being joined together by interlocking the slotted portions thereby forming a plurality of cells between the sides of the adjacent beams, the panels fitting in the cells and resting on the beam shoulders, means to retain the panels against the shoulders, comprising flanges extending outwardly from the edges of the beams over the edges of the panels, and wedge members inserted 15 between the sides of each beam.
8. An interlocked structure comprising a plurality of U-shaped beams undercut at spaced intervals by slots having width of the beams, the beams being joined together at right angles to each other by interlocking the undercut portions thereby forming a plurality of rectangular cells, panels placed on the bridge portions of the longitudinal beams and abutting the edges of the transverse beams, and flanged wedge members 20 inserted between the sides of the beam, the flanges extending over the edges of the panels for holding them against the bridge portions of the beams.
9. An interlocked structure comprising a plurality of U-shaped beams undercut at spaced 25 intervals by slots having width of the beams, the beams being joined together at right angles to each other by interlocking the undercut portions thereby forming a plurality of rectangular cells, panels placed on the bridge portions of the longitudinal beams and abutting the edges of the transverse beams, and flanged wedge members 30 inserted between the sides of the beam, the flanges extending over the edges of the panels for holding them against the bridge portions of the beams.
35. 10. An interlocked structure comprising a plurality of U-shaped beams undercut at spaced intervals by slots having width of the beams, the beams being joined together at right angles to each other by interlocking the undercut portions thereby forming a plurality of rectangular cells, wedge members inserted between the outer 40 portions of the sides of the beams for pressing the sides of the beams against the abutting edges of the transverse beams, and means to lock together the abutting portions of the beams by the wedge members, said means comprising mutually engaging notches and ribs.
45. 10. An interlocked structure comprising a plurality of U-shaped beams undercut at spaced intervals by slots having width of the beams, the beams being joined together at right angles to each other by interlocking the undercut portions thereby forming a plurality of rectangular cells, wedge members inserted between the outer 50 portions of the sides of the beams for pressing the sides of the beams against the abutting edges of the transverse beams, and ribs on the solid sides of the beams, the edges of the beams at the slots having notches for engaging the ribs.

HIPPOLYTE W. ROMANOFF.
